UNITED STATES PATENT OFFICE.

JOHN L. CLARK, OF ROCKFORD, ILLINOIS.

FLUE-STOPPER.

SPECIFICATION forming part of Letters Patent No. 662,220, dated November 20, 1900.

Application filed March 19, 1900. Serial No. 9,234. (No model.)

To all whom it may concern:

Be it known that I, JOHN L. CLARK, a citizen of the United States, residing at Rockford, in the county of Winnebago and State of Illinois, have invented certain new and useful Improvements in Flue-Stoppers, of which the following is a specification.

The object of this invention is to construct a flue-stopper in which two bows are pivotally connected to the plate of the stopper in a manner to fold, so that they may be closely packed.

In the accompanying drawings, Figure 1 is an isometrical representation of my improved flue-stopper with the bows extended. Fig. 2 is a similar representation, in which the bows are folded; and Fig. 3 is a view of the outer face of the plate of the stopper, showing the clamps holding the bows in connection with the plate. Fig. 4 is a section of the base and center plate, showing their connection.

The plate 1 of the stopper is of circular form and may be ornamented in any suitable manner to meet the requirements of the trade. The center portion of the plate has four perforations. A clamping-plate 2 has four semicircular recesses 3, arranged radially from the center of the plate, and has four ears 4, passing through the perforations in the plate of the stopper and clenched, as shown at Fig. 3. Two bows 5 and 6 are of the same size and shape, having their ends located in the recesses 3 in the clamping-plate, thereby forming a

pivotal connection between the bows and the plate of the stopper, and are so located that they cross each other, and at the point of crossing the bow 5 has a bend 7 in an upward direction and the bow 6 a bend 8 in a downward direction, so that when the bows are in the position shown at Fig. 1 a connection will be formed between them, holding them in proper position to enter the flue. The bows can be folded into the position shown at Fig. 2 for shipment, occupying a small space.

I claim as my invention—

1. In a flue-stopper, the combination of a base-plate, a center plate connected with the base-plate having four semicircular recesses extending radially from the center of the plate, and two bows having their ends located in the recesses and adapted to cross each other when extended.
2. In a flue-stopper, the combination of a base-plate, a center plate connected with the base-plate having four semicircular recesses extending radially from the center of the plate, and two bows having their ends located in the recesses and adapted to cross each other when extended, their crossing-points formed with notches which engage each other and hold the bows in their extended position.

JOHN L. CLARK.
